(57) **CLAIM**

The ornamental design for a foothold for climbing treestands, as shown and described.

DESCRIPTION

FIG. 1 is a perspective view of a foothold pair for climbing treestands and shown attached to a climbing treestand. The broken lines are for illustrative purposes only and form no part of the claimed design.

FIG. 2 is a left side elevation view of the footholds for climbing treestands as shown in FIG. 1;

FIG. 3 is a right side elevation view of the footholds for climbing treestands as shown in FIG. 1;

FIG. 4 is a front view of the footholds for climbing treestands as shown in FIG. 1;

FIG. 5 is a rear view of the footholds for climbing treestands as shown in FIG. 1;

FIG. 6 is a top plan view of the footholds for climbing treestands as shown in FIG. 1; and,

FIG. 7 is a bottom plan view thereof of the footholds for climbing treestands as shown in FIG. 1.
